UNITED STATES PATENT OFFICE.

ALFRED F. HOWE, OF NUTLEY, NEW JERSEY, ASSIGNOR TO THE BORDEN COMPANY,
OF WARREN, OHIO, A CORPORATION OF OHIO.

PIPE-CUTTER.

1,040,202.

Specification of Letters Patent.

Patented Oct. 1, 1912.

Application filed October 30, 1911. Serial No. 657,564.

To all whom it may concern:

Be it known that I, ALFRED F. HOWE, of Nutley, in the county of Essex and State of New Jersey, have invented certain new and 5 useful Improvements in Pipe-Cutters; and I do hereby declare the following to be a full, clear, and exact description of the invention, such as will enable others skilled in the art to which it appertains to make and 10 use the same.

The primary object of this invention is to provide an extremely simple and inexpensive pipe cutter wherein the knives will be automatically fed and regulated in their 15 work after the centering jaws are moved into pipe-engaging position, and which may be used for cutting pipes of different sizes without the necessity of changing the cutters.

20 The invention will be hereinafter fully set forth and particularly pointed out in the claims.

In the accompanying drawings, Figure 1 is a view in side elevation. Fig. 2 is an 25 opposite side view. Fig. 3 is a longitudinal sectional view on line 3—3, Fig. 1. Fig. 4 is a diagrammatical view showing the positions of the cutters relatively to the centering jaws both before and after the latter 30 engage a pipe.

Referring to the drawings, 1 designates a frame having at its ends internally threaded sockets for manipulating handles 2 and 3, the former extending through its socket and 35 capable of being moved longitudinally of the frame, while the handle 3 remains fixed. The frame has at one side a fixed centering jaw 4 of V-shape, and on the other side, opposite this jaw, and in line with the body 40 of the frame, is a housing 5 for a block 6, which is normally held against a stop 7 by a heavy coil spring 8 located within the housing.

9 is an adjustable jaw of V-shape, slidably mounted on frame 1, and extending laterally therefrom in the plane of the fixed jaw, and at one side this adjustable jaw carries a housing 10 in line with housing 5. Within the former is a block 12 which is normally 50 held against a stop 13 by a heavy coil spring 14. Both the housings are open at their inner opposite ends. In an ear 15 of the adjustable jaw is fitted the inner end of handle 2.

55 16 designates cutters and 17 regulating

guides therefor. I employ two cutters and two guides, and preferably form each cutter and its respective guide from a single plate with a throat or clearance between them, and each guide is depressed with reference 60 to its cutter whose action it limits. The cutter and guide plates are shown as bolted to blocks 6 and 12, and it will be noted that the cutters and guides are equi-distant on opposite sides of the centers of the pipe engaging 65 jaws, so that, regardless of the size of the pipe, the cutters and guides will contact therewith at substantially the same points on opposite sides of a plane passing longitudinally through the axis of the pipe and 70 intersecting the centers of the jaws. As the jaws clamp a pipe the springs are put under tension; that is to say, by the act of adjusting the tool to a pipe the cutters are brought into position ready for cutting, and in consequence no further turning of the adjustable handle or any other part is necessary 75 to effect the desired cut, the cutters being spring-fed. The cutters are moved toward each other as the work progresses, the jaws 80 retaining their relative positions, and the depth of the cut in each rotation of the tool is limited by the guides.

Inasmuch as the cutters and their guides are equi-distant on opposite sides of a plane 85 passing longitudinally through the axis of the pipe to be cut and intersecting the centers of the two jaws, regardless of the size of the pipe, the necessity of substituting different cutters and guides in changing 90 from one size pipe to another, is obviated; and by making each cutter and its guide from a single plate a relative adjustment of their parts is unnecessary, and I thereby 95 avoid the danger of improperly setting the parts.

I claim as my invention:—

1. A pipe cutter comprising a frame having oppositely disposed centering jaws between which there is a relative adjustment, means for effecting such adjustment, opposed cutters slidably mounted on said jaws, springs acting on said cutters and designed to be placed under tension by the engagement of the cutters with a pipe as the jaws 105 are brought into pipe-clamping position, and guides for limiting the action of the cutters.

2. A pipe cutter comprising a frame having oppositely disposed centering jaws be- 110

5 tween which there is a relative adjustment, means for effecting such adjustment, opposed cutters slidably mounted on said jaws, springs acting on said cutters and designed
 10 to be placed under tension by the engagement of the cutters with a pipe as the jaws are brought into pipe-clamping position, and guides in advance of the cutters for limiting the action of the cutters, the cutters
 15 and guides being equi-distant on opposite sides of the centers of the jaws, the pipe-engaging ends of said guides being on a greater radius than the cutters.

3. A pipe cutter comprising a frame having oppositely disposed centering jaws between which there is a relative adjustment, means for effecting such adjustment, oppositely disposed carriers mounted on the jaws, springs acting on the carriers, plates secured
 20 to said carriers, each plate having a cutter and a guide with a clearance between them, each guide being in advance of its respective cutter, depressed relatively thereto, and said cutters and guides being equi-distant on opposite sides of the centers of
 25 the opposed jaws.

4. A pipe cutter comprising a frame having two jaws extending laterally therefrom in line with each other, one jaw being fixed
 30 and the other adjustable, and an adjustable handle carried by said frame and engaging the adjustable jaw, each of said jaws having a housing open at its inner end, carrier blocks fitted in said housings, stops for said
 35 blocks, springs within the housings acting on said blocks, and cutters and guides carried by said blocks with a clearance between each cutter and its respective guide, such cutters and guides being equi-distant on

opposite sides of the centers of said jaws, 40 the pipe-engaging ends of said guides being on a greater radius than the cutters, and said springs being placed under tension, by the engagement of the cutters with a pipe when the jaws are brought into pipe-engag- 45 ing position.

5. A pipe cutting tool comprising pipe-clamping jaws between which there is a relative adjustment as the tool is being applied to a pipe, said jaws maintaining a fixed 50 relation to each other during the cutting operation, spring-actuated cutting means coöperating therewith and designed to be placed under tension by engagement with a pipe by bringing the jaws into pipe-clamping position, and guiding means for limiting the action of the cutting means. 55

6. A pipe cutting tool comprising pipe-clamping jaws between which there is a relative adjustment as the tool is being applied 60 to a pipe, said jaws maintaining a fixed relation to each other during the cutting operation, spring-actuated cutting means movable co-currently with, and relatively to, the jaws as the latter are being adjusted 65 and designed to be placed under tension by engagement with a pipe as the jaws are brought into pipe-clamping position, and guiding means for limiting the action of the cutting means. 70

In testimony whereof, I have signed this specification in the presence of two subscribing witnesses.

ALFRED F. HOWE.
